(57) **CLAIM**

The ornamental design for a lamp, substantially as shown and described.

DESCRIPTION

FIG. 1 is a perspective front view of a lamp showing my new design;

FIG. 2 is a front elevational view thereof, the rear being a mirror image;

FIG. 3 is a right side view thereof, the left side being a mirror image; and,

FIG. 4 is a top plan view thereof.

The broken line showing of environmental structure is for illustrative purposes and does not form a part of the claimed design.

1 Claim, 4 Drawing Sheets

FIG. 1

FIG. 2

FIG. 4
